(57) **CLAIM**

The ornamental design for a motorcycle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a left perspective view of a motorcycle showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right perspective view thereof;

FIG. 9 is a partial enlarged view of the portion of FIG. 1 outlined by the dot-dash broken line;

FIG. 10 is a partial enlarged view of the portion of FIG. 1 outlined by the dot-dash broken line;

FIG. 11 is a partial enlarged view of the portion of FIG. 1 outlined by the dot-dash broken line;

FIG. 12 is a partial enlarged view of the portion of FIG. 1 outlined by the dot-dash broken line;

FIG. 13 is a partial enlarged view of the portion of FIG. 1 outlined by the dot-dash broken line;

FIG. 14 is a partial enlarged view of the portion of FIG. 1 outlined by the dot-dash broken line;

FIG. 15 is a partial enlarged view of the portion of FIG. 1 outlined by the dot-dash broken line;

FIG. 16 is a partial enlarged view of the portion of FIG. 1 outlined by the dot-dash broken line;

FIG. 17 is a partial enlarged view of the portion of FIG. 8 outlined by the dot-dash broken line;

FIG. 18 is a partial enlarged view of the portion of FIG. 8 outlined by the dot-dash broken line;

FIG. 19 is a partial enlarged view of the portion of FIG. 8 outlined by the dot-dash broken line;

FIG. 20 is a partial enlarged view of the portion of FIG. 8 outlined by the dot-dash broken line;

FIG. 21 is a partial enlarged view of the portion of FIG. 8 outlined by the dot-dash broken line;

FIG. 22 is a partial enlarged view of the portion of FIG. 8 outlined by the dot-dash broken line;

(Continued)

FIG. 23 is a partial enlarged view of the portion of FIG. 8 outlined by the dot-dash broken line;

FIG. 24 is a partial enlarged view of the portion of FIG. 8 outlined by the dot-dash broken line; and,

FIG. 25 is a partial enlarged view of the portion of FIG. 8 outlined by the dot-dash broken line.

The dot-dash broken lines in FIGS. 1 and 8-25 are provided for annotative purposes to graphically indicate the areas of enlargement. These dot-dash broken lines do not represent actual structure and do not form part of the claimed design.
